UNITED STATES PATENT OFFICE.

REUBEN STEINBERG, OF NEW YORK, N. Y.

AUTOMOBILE EXHAUST GENERATOR PROPULSION.

Application filed March 20, 1924. Serial No. 700,739.

To all whom it may concern:

Be it known that I, REUBEN STEINBERG, a citizen of the United States, residing at New York, in the county of New York and 5 State of New York, have invented certain new and useful Improvements in Automobile Exhaust Generator Propulsion, of which the following is a specification.

The main object of this invention is to 10 provide a gas propulsion means which uses the exhaust gases of a combustion engine to drive a fan or the like which may be coupled to a generator or other mechanism.

Another object is to provide an exhaust 15 gas propulsion fan and an additional auxiliary wind driven fan which are mounted on a generator drive shaft and are coupled so that the gas propelled fan may be rotated independently of the air propelled fan, a 20 novel clutch means being provided between both fans to accomplish the purpose.

Another object is to provide a means of 25 diluting the exhaust fumes of a combustion engine by the exhaust itself and aided by the air currents caused by the motion of the engine.

These and other objects will become apparent in the description below, in which characters of reference refer to like-named 30 parts in the drawing.

Referring briefly to the drawing, Figure 1 is a side elevational view, showing the generator propulsion unit as applied in combination with a combustion engine.

35 Figure 2 is a top plan view of the same.

Figure 3 is a sectional view taken longitudinally and centrally thru the generator shaft propelling unit.

Figure 4 is a front elevational view of 40 Figure 3.

Figure 5 is a cross sectional view taken on line 5—5 of Figure 3.

Figure 6 is a fragmentary elevational view 45 of the clutch mechanism mounted between the fan units.

Referring in detail to the drawing, the 50 numeral 10 indicates a combustion engine having four cylinders. From each cylinder, an exhaust outlet 11 leads which communicates with a manifold 12, said manifold ordinarily passing rearward to enter into a muffler 13. An automobile is usually provided with a generator 14 or a similar unit which is usually geared to the crank or cam 55 shaft of the engine, but in this case, is propelled by my device which consists essen-

tially of a small semi-circular casing 15 and a larger casing 16, both casings being joined by a flanged sleeve 17 and are mounted about a common axis. The shaft 60 18 of the generator passes entirely thru the casing and partly thru the casing 16, the latter having a funnel face 19 at its outer end in which a large opening 20 is provided. An inlet opening 21 is provided 65 in the casing 15 at one side, this opening communicating with the manifold 12 before it enters the muffler 13, and an opening 22, provided opposite to the opening 21, communicates with the muffler thru a pipe 23. 70 Within the casing 15 and mounted on the shaft 18, a hub 24 is rigidly secured to said shaft and has a plurality of radially extending arms 25 thereon to which longitudinally curved fan blades 26 are riveted, the width 75 of said fan blades extending in a parallel direction with the axis of rotation. In the casing 16, an additional hub 27 is rotatably mounted on the shaft 18 between collars 28, the latter being fixed to the shaft 18 by pins 80 or other similar means. Fan blades 29 extend radially from the hub 27, the width of said blades being angular with respect to the axis of rotation. An outlet 30 is provided in the casing 16 and has a tube 31 communicating therewith which extends rearward and enters into a tube 32 which extends from the rear end of the muffler 13. Between the hubs 24 and 27 of the fan members, an additional collar 33 is mounted which has a flange 34 formed thereon. This flange is provided with a plurality of teeth 35 at diametrically opposite positions on the face, said teeth being engageable with a resilient tongue 36, the latter being mounted on the 90 adjacent face of a flange 37 which extends from one end of member 27.

The device in being used, rotates the generator 14 which is used for providing electrical energy. This is accomplished by passing 100 exhaust gases from the cylinders of the combustion engine thru the manifold and into the casing 15 thru the inlet 21. These gases strike the curved fan blades 26 in said casing and rotate the generator shaft 18 as the hub 24 of the fan unit is rigidly secured to said shaft. The exhaust gases then pass out of the casing 15 thru the outlet 22 and into the muffler 13 thru the pipe 23 to be emitted finally thru the tube 32. The auxiliary fan mounted in the casing 16, is used 105 as an aid to reduce the power load of the fan 110

member in the casing 15. As air currents enter the opening 20 of the casing 16, the fan blades 29 and hub 27 are rotated. When no air enters the opening 20, these fan blades 5 and hub 27 may remain stationary, as said hub is not rigidly mounted on the generator shaft 18, but when air does enter, the resilient tongue 36 engages a tooth 35 mounted on the flange 34 and in this manner, aids in 10 rotating the shaft 18.

I claim:

A device of the class described used in combination with combustion engines and comprising a casing and an additional larger 15 casing connected by a sleeve, said casings having a common axis, a shaft passing axially thru said casings, a fan rigidly mount-

ed on on said shaft in the smaller casing, the fan blades of said fan being curved longitudinally, the larger casing having an opening 20 at the side, a fan rotatably mounted on said shaft in the larger casing, a hub, angular fan blades on said hub, a flange on said hub, a resilient tongue on the face of said flange, a collar secured to said shaft, a flange on said collar adjacent the flange of the hub member, a plurality of teeth on the face of the first-named flange, said teeth being adapted to be engaged by the resilient tongue, said teeth when engaged by the tongue being adapted to rotate the flange thru the medium 25 of the fan blades in the larger casing.

In testimony whereof I affix my signature.

REUBEN STEINBERG.
